UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-RECEPTACLE.

52,480.

Specification for Design. Patented Sept. 24, 1918.

Application filed February 19, 1915. Serial No. 9,443. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Powder-Receptacle, of which the following is a specification, reference being had to the accompanying drawing, forming a part thereof.

On the drawing:

The figure is a perspective view of the powder receptacle embodying the said design.

The design is characterized by a cylin-

drical flattened body having a depressed flat top surrounded by a marginal raised bead, said depressed top being surmounted by a cylindrical cover of relatively small diameter and height, as compared with the body of the box, having an arched dome-shaped top.

I claim:

The ornamental design for a powder receptacle, as shown.

EDMUND HOFFMAN.
